UNITED STATES PATENT OFFICE.

ADAM WOOD, OF PITTSBURGH, PENNSYLVANIA.

OSCILLATING STEAM-ENGINE.

Specification of Letters Patent No. 19,057, dated January 5, 1858.

To all whom it may concern:

Be it known that I, ADAM Wood, of Pittsburgh, in the county of Allegheny and State of Pennsylvania, have invented certain new and useful Improvements in Oscillating Steam-Engines; and I do hereby declare that the following is a full, clear, and exact description of the same, reference being had to the accompanying drawings, making a part of this specification, in which—

Figure 1, is a side view of an engine with my improvements, shown as having the cover of the steam chest taken off, and the eduction pipe taken away. Fig. 2 is a section of the cylinder, steam chest, and valve for induction and eduction of steam, taken in a plane passing through the longitudinal axis of the cylinder and through its axis of oscillation. Fig. 3, is a transverse section 20 of the cylinder, steam chest, and induction and eduction valve, exhibiting also sections of the induction and eduction pipes. Fig. 4, exhibits the face of the valve shown in Figs. 1, 2, and 3.

Similar letters of reference indicate corresponding parts in the several figures.

This invention consists in the employment of a treble-armed, centrally-balanced valve, substantially as hereinafter described.

A, Figs. 1, 2, and 3, is the cylinder, having two solid trunnions a , a^1 , which are fitted to work in bearings b , b^1 , supported on the bed-plate K, in the usual manner.

B C, is a steam chest, bolted by bolts c , c , to one side of the cylinder, and near the ends thereof, and so formed as to stride across the outside of the bearing b^1 , of the trunnion, a . This steam chest is in the form of two sectors of circles described from a center in line with the axis of oscillation of the cylinder, as shown in Fig. 1. In the back part B, of the steam chest, or part nearest the cylinder, there are two ports d , d^1 , leading one to each end of the cylinder.

D, is the valve by which the induction and eduction of the steam is effected; said valve extending across the interior of the steam chest, and fitting to two seats e , e^1 , in which are the ports d , d^1 . The valve is made entirely hollow, with three arms f , f^1 , f^2 , two of which, viz., f^1 , f^2 , are faced to fit to the seat e^1 , and the other f , is faced to fit to the seat e ; and these arms have each one port, communicating with the hollow interior of the valve; the said ports corresponding in size with the ports d , d^1 , in the steam chest,

and occupying such a position relatively to the axis of oscillation, that the oscillation of the cylinder will bring the port g , of the arm f , into communication with the port d , and either the port g , of the arm f , or that g^1 , of the arm f^1 , according to the position of the valve, into communication with the port d^1 , for the purpose of exhausting the steam from the cylinder through the interior of the valve to the eduction pipe E, the inner end of which fits to the valve opposite to the trunnion a^1 , as shown at s , s , Figs. 2 and 3, with a steam-tight joint. The valve is stationary, except to reverse the engine. The eduction pipe is also stationary. The valve is kept in place by a stud t , at its center, fitting to a seat or bearing in the back of the steam chest, and prevented turning by a square on the said stud, fitting to a corresponding square in a lever H, which is locked in a stationary condition when the engine is in operation, but is capable of being moved to shift the valve, to reverse the engine. By having the valve D supported centrally by the stud (t), it is prevented from an undue bearing at its ends upon the valve seat. The stud (t) thus serves as a central fulcrum or balance point for the valve D.

F, is a stationary box, surrounding the eduction pipe, for the purpose of receiving the live steam from the induction pipe I, and delivering it into the steam chest B, C. This box is surrounded by a passage i , with which the induction pipe connects; and between this passage and the interior of the box, there is a screw stop valve j , Fig. 3, which serves to shut off, and, if desired, to regulate, the supply of steam.

The operation of the valve, and its appurtenances, is as follows:—The oscillation of the cylinder uncovers the ports d , d^1 , alternately, and allows steam to enter from the steam chest; and as one of the said ports is uncovered, the opposite one is brought into communication with one of the ports in the valve, to allow the steam to exhaust through the valve.

In Fig. 1, of the drawing, the port d^1 , is shown to be entirely uncovered, and the port d , to be in full communication with the port of the arm f , of the valve; the ports of the valve being all shown in red outline; and consequently the piston is moving to the left, and the crank rotating in the direction of the arrow shown upon it. The piston is now at

"half stroke." As the motion continues, the port d^1 , passes under the port m^1 , of the face of the arm f^1 , of the valve, and is thereby gradually closed; while, at the same time, 5 the port d , passes under the port m , of the arm f , of the valve, and is thereby gradually closed; both ports being closed by the time the engine arrives on its center. As 10 the engine passes its center, the port d^1 , moves upward under the port g^1 , and commences exhausting; and the port d , moves downward from under the port m , of the face of the arm f , and commences taking steam; the port d^1 , being full open, and the 15 port d , being in full communication with the exhaust port, g^1 , when the engine arrives at the middle of the stroke; after which the port d moves up under the port m , of the valve, and commences closing, and the port 20 d^1 , moves down under the port m^1 , so that both ports are again closed at the end of the stroke; but after the engine again passes the center, the port d^1 again commences opening, and the port d , commences to make communication with the exhaust port g . It will 25 be understood that during the above described operation, the arm f^* , of the valve, and the face m^2 , of the arm f , are of no use; but if the valve is turned, by means of the 30 lever H , a distance equal to twice the width of the ports d , d' , taken in a circumferential direction, the arm f^1 , of the valve, is thrown out of operation, and that f^* , thrown into operation; and the port g^* , and face m^* , of 35 the arm f^* , are caused to operate relatively

to the port d^1 , as the port g^1 , and face m^1 , previously did, and the face m^2 , of the arm f , to operate relatively to the port d , as the face m , previously did, and the port g , to operate just the reverse; by which means the 40 direction of the engine is changed. The lever H , is secured in either of the necessary positions by springing into notches in a stand J .

When an engine is made that is never required to be reversed, its cost may be reduced by making the valve with two arms only. The construction of that valve, however, needs no particular description, as it will be essentially the same as the valve D , 45 with one of the arms f^1 , or f^* , omitted. When the valve is made in that way, it may be cast with the eduction pipe E , if desired, as it never requires any motion.

I do not claim the exhaustion of the steam 50 through the valve; nor do I claim broadly the attachment of the steam chest to the cylinder, to oscillate therewith, and operate in combination with a stationary valve.

Having thus described my invention, what 55 I claim as new, and desire to secure by Letters Patent, is:—

The employment of a treble-armed, centrally-balanced valve, D , substantially as herein described.

ADAM WOOD.
